Des. 200,072
Patented Jan. 12, 1965

200,072

PORTABLE IMPACT TOOL OR THE LIKE

Albert C. Koett, 2112 Glenside Ave., Norwood, Ohio

Filed June 20, 1963, Ser. No. 75,454

Term of patent 14 years

(Cl. D54—14)

Fig. 1

FIG. 1 is a rear perspective view of one side of a portable impact tool or the like showing my new design; the opposite side is the same as the side illustrated.

FIG. 2 is a front perspective view of the same side thereof.

FIG. 3 is a front elevational view thereof.

I claim:

The ornamental design for a portable impact tool or the like, as shown and described.
